UNITED STATES PATENT OFFICE

150,196

DESIGN FOR A COMBINATION LIGHTER,
TAMPER, AND KNIFE

Irwin G. Bauer, Cincinnati, Ohio

Application September 7, 1946, Serial No. 133,164

Term of patent 7 years

(Cl. D48—27)

To all whom it may concern:

Be it known that I, Irwin G. Bauer, a citizen of the United States, residing at Cincinnati, in the county of Hamilton and State of Ohio, have invented certain new, original, and ornamental design for a combination lighter, tamper, and knife, of which the following is a full, clear, and exact description, reference being had to the accompanying drawings, forming a part thereof.

In the drawings:

Fig. 1 is a plan view taken from the top of a combination lighter, tamper, and knife, showing my new design.

Fig. 2 is a side elevation of a combination lighter, tamper, and knife, showing my new design.

Fig. 3 is a front elevation of a combination lighter, tamper, and knife, showing my new design.

Fig. 4 is a plan view taken from the bottom of a combination lighter, tamper, and knife, showing my new design.

Fig. 5 is an exploded view of a combination lighter, tamper, and knife, showing my new design.

The dominant features of my design reside in the configuration and arrangement of the lower bowl portion together with the connecting stem.

I claim:

The ornamental design for a combination lighter, tamper, and knife, as shown and described.

IRWIN G. BAUER.
